EDWARD G. RAGATZ, OF LOS ANGELES, CALIFORNIA, ASSIGNOR TO UNION OIL COMPANY OF CALIFORNIA, OF LOS ANGELES, CALIFORNIA, A CORPORATION OF CALIFORNIA

METHOD FOR THE DISTILLATION OF PETROLEUM

Application filed November 6, 1926. Serial No. 146,672

The invention relates to methods and apparatus for distilling and fractionating petroleum feed material (either crude or partially rectified) into a residual or heavy cut and one or more overhead or light cuts, the terms "heavy" and "light" being used in a relative sense only. The primary object of the invention is to obtain all such cuts in forms sharply defined from one another, the method and apparatus being adapted to the production of successive sharp cuts from the original feed stock in successive units of apparatus wherein the residual cut from one unit is further sharply cut in another unit of substantially the same type. With this process, the distillation and separation of the original feed material is effected in such a manner that the initial vaporization temperature of the residual cut, as determined by a standard Engler distillation apparatus, is equal to or greater than the maximum Engler distillation temperature of the heaviest overhead cut, indicating a maximum yield of overhead material. The entire operation is carried out at temperatures low enough to effectively suppress any tendency towards cracking on the part of either the original feed material or its distillation products.

Briefly outlined, the invention comprises:—
1. The initial heating of a feed material to at least that minimum temperature necessary for the effective operation of the process, this temperature usually approximating the temperature of the vapors in a distilling column at the point where the feed material is introduced.

2. The introduction of this heated feed material onto a feed plate of said column wherein the vapors formed during the initial heating operation are released, and wherein the hot remaining liquid is subsequently brought into intimate contact with a counter-currently flowing stream of hotter vapors in a portion of the column referred to as an "exhausting" section.

3. The removal, as a result of the aforementioned intimate contact maintained between counter-currently flowing streams of cooler liquid and hotter vapors, of most of the de-

sired overhead material content of the liquid portion of the feed.

4. The extraction of the denuded, or exhausted, liquid from the aforementioned column and its subsequent heating in an exhausting heater (preferably tubular) to a temperature sufficient to furnish the hot recycling vapors required for the aforementioned exhausting operation; this heating also serving to vaporize the last of the overhead-material content of the exhausted liquid.

5. The separation, in an exhausting vapor separator apart from the heating elements of the exhausting heater, of the aforementioned exhausting vapors, and their subsequent introduction into the exhausting section of the aforementioned column.

6. The extraction of the remaining liquid from the exhausting vapor separator to form the desired residual or heavy cut.

7. The introduction of the vapors arising from the aforementioned feed plate into a washing and fractionating section wherein these vapors are brought into intimate counter-current contact with a colder liquid reflux material for the purpose of removing the undesirable heavy fractions entrained and vaporized at the aforementioned feed plate.

8. The introduction, in case several overlapping overhead cuts are desired, of the initially fractionated vapors into an additional fractionating section wherein they are separated and condensed to form the desired overlapping light material cuts by being brought into intimate counter-current contact with a still colder liquid reflux material.

9. The maintenance of a minimum amount of liquid material in the system in order to make possible quick adjustments of control.

10. The introduction of steam into any portion in the system, the carrying of a part or all of the system under a vacuum, or the combination use of steam and vacuum, for the purpose of lowering the temperatures under which the system operates; this lowering of temperature being for the purpose of improving the quality of the resultant products, for the suppression of cracking, or for both.

It should be noted that the invention re-

sides not only in the points developed in the above outline, but also in all other novel features, steps or combinations thereof presented elsewhere in the disclosure.

5 In the accompanying drawings wherein certain embodiments of the invention are shown by way of illustration and wherein two sets of apparatus suitable for the operation of the process are outlined,

10 Fig. 1 discloses diagrammatically an installation comprising two complete units;

Fig. 2 is a cross section taken on line 2—2 of Fig. 1;

15 Fig. 3 is a cross section taken on line 3—3 of Fig. 1;

Fig. 4 discloses diagrammatically an installation comprising a single unit used in conjunction with fractionating apparatus suitable for the production of a plurality of 20 overlapping overhead light cuts;

Fig. 5 is a cross section taken on the line 5—5 of Fig. 1;

Fig. 6 is a section taken on the line 6—6 of 25 Fig. 5;

Fig. 7 is a cross section taken on the line 7—7 of Fig. 4; and

Fig. 8 is a section taken on the line 8—8 of Fig. 2.

As illustrated, the feed stock is brought 30 into the apparatus thru a line 1 by means of a pump P and conducted through heat exchanges 2 to a tubular feed heater 3, various pumps P being used throughout the system wherever required. From the feed heater 3, 35 wherein the stock is heated to a predetermined degree, the feed is led by a line 4 into a central portion of a distilling and rectifying column E wherein the said feed stock is discharged onto a distributing or feed plate 5.

40 The feed heater 3 is controlled so as to produce a feed temperature, as determined by the thermometer 6, equal to, or 2 to 10° F. higher than, the temperature of the vapors immediately above the feed plate 5. The optimum feed temperature is that of the vapors immediately above the feed plate, but in operating practice it is found advisable to heat the said feed 2 to 10° F. higher than these vapors in order to be sure that the optimum 45 temperature has been reached. The temperature of these vapors may be determined by a thermometer 7 positioned well above the feed plate 5 and so protected that it avoids being splashed by the entering feed stock.

55 At the feed plate 5 the vapor content of the heated feed stock is released and the remaining liquid uniformly distributed over the top of an exhausting section 8 containing spiral tile or the like. The feed then flows by gravity down thru the exhausting tile constituting the section 8, encountering and being brought into intimate contact with an ascending current of hotter vapors. This 60 counter-current intimate contact of ascend-

ing hotter vapors with descending colder liquid feed results in the boiling out from the liquid of most of its desired light cut fractions. Thus the exhausted stock, when it falls into the chamber 9 at the bottom of the column E, contains only a small amount of the heaviest of those fractions which ultimately go to make up the desired light material cuts.

65 From the chamber 9 the hot bottoms are withdrawn by means of another pump P and forced through the line 10 to a tubular exhausting heater H. At the heater H the hot denuded stock is forced through the heating coils 11, being mixed with superheated steam at the steam inlet connection 12. The heater H is fired to a temperature, as determined by the thermometer 13, sufficient to free the stock of its remaining light material content and to furnish the quantity of continuously 70 recycling vapors required for the exhausting of successive increments of feed stock in the exhausting section 8, these vapors being continuously condensed and returned to heater H along with the denuded stock. The introduction of superheated steam at point 12 in the still coils makes it possible to avoid the cracking of the exhausted feed stock while vaporizing the required quantity of 75 lighter material.

80 The mixture of hot liquid and vapors leaving the exhausting tubular heater H is forced through the line 14 to the exhausting vapor separator S, in which the vapors are separated from the liquid and from which they 85 are conducted through the line 15 to the compartment 9 beneath the exhausting section 8 in the column E.

85 In the vapor separator S, the mixture of liquid and vapors is discharged onto the uppermost of a plurality of vaporizing trays 16, and in passing down over these trays, presents a large surface to the vapor space within in the separator with the result that the vapors are readily separated from the liquid, yielding a residual material free from entrained vapor fractions. This residual material settles into compartment 17 at the base of separator S while the liberated vapors 90 pass up through annular spaces 18 between the vaporizing trays and the separator shell and thence to the line 15.

95 The hot residual liquid now free from vapors and light constituents is withdrawn from the base of the separator S through the line 19 and another pump P. This material constitutes the desired residual or heavy cut of the original feed stock, and may be passed either to storage by way of line 19 and heat exchanger 2, or by-passed through valve 19' 100 to be subjected to further treatment in a second unit substantially like the one just described and comprising a preheater 3', an exhausting column E', a heater H' and a vapor separator S', which are employed to produce 105

further sharply defined cuts from said residual material.

From feed plate 5 the vapors released from the initially heated feed stock, together with an ascending stream of hot vapors from the 5 exhausting section pass upward into a wash- ing section 20 consisting of a second column of spiral tile or the like.

This wash column, according to the form of Fig. 1, receives reflux from a superimposed rectifying or fractionating column R provided with a series of screen fractionating trays 21 equipped with suitable reflux down- flow tubes 21'; the lowermost tray being constructed to uniformly distribute said reflux over the top of the column of wash tile 20 whereby the heavier constituents of the rising vapors are washed out and returned to the exhausting section 8 by the counter-current scrubbing action of the descending re- flux. The vapors which rise from the top tray of the fractionating column R are conducted by line 22 to a reflux condenser 23 wherein the heavier portions are condensed and returned by line 24 to the top plate 21 of the section R. The desired light cut from reflux condenser 23 is then passed by way of condenser C to a receiving tank T, which if desired may be placed under vacuum by 10 means of vacuum pump V. In order to control the temperature and the rectifying conditions in section R the character and temperature of the reflux from condenser 23 may be regulated by the introduction of a quantity of the light cut from receiving tank T into the reflux line 24 by way of a line 25. The excess of the light cut is conducted from receiving tank T to the storage reservoir T'.

According to the form of Fig. 4, vapors from the top of the wash section 20 in column E are passed by way of line 26 into a chamber 27 at the bottom of a primary rectifying or fractionating column R' which performs substantially the same function as column R of Fig. 1. At the same time the bottoms from said column R', are picked up by a pump P from the chamber 27 and conducted through a line 28 to a distributor plate 20' located above the section 20 of wash tile. These fractionator bottoms are uniformly distributed over the top of the column of wash tile 20 by said distributor plate 20' and flow by gravity down through the wash column, encountering and being brought into intimate contact with the aforementioned ascending stream of released and recycling vapors. This counter-current scrubbing of the vapors by the fractionator bottoms serves to remove the liquid feed material entrained at the feed plate 5. The refluxed fractionator bottoms containing the entrained liquid feed material then mixes with the original feed stock on the plate 5 and continues on down through the 5 exhausting column 8, being subjected to the

same exhausting action as, and becoming to all appearances a part of, the original feed.

The vapors conducted from the top of the wash column 20 through the line 26 to the compartment 27 contain undesirable heavy fractions which were vaporized within the exhausting column E and which are to be removed in the rectifying column R'. This latter column is composed of a plurality of screen bottomed fractionating trays 29 pro- 70 vided with suitable reflux downflow tubes 29', like trays 21 and tubes 21'. The ascending vapors within this column enter succeeding trays through the screen bottoms and inti- mately mix with the liquid held on these trays, while the descending reflux liquid gravitates from screen to screen via said re- flux tubes. Reflux liquid for the operation of said column R' is obtained from the compartment 30 in the base of a secondary frac- 75 tionating column F and forced via the line 31 to the top screen of the primary fractionat- ing column R'. The intimate counter-current contact thus obtained between ascending va- 80 por and descending reflux liquid yields a vapor overhead at the top of the fractionat- ing column R' which is entirely freed of all undesirable heavy fractions. These vapors are then conducted via the line 32 to the com- 85 partment 30 preparatory to being separated and condensed into the desired overhead, or light, cuts. The quality of the overhead va- 90 por from primary fractionator R' is main- tained by controlling the quantity of reflux pumped into the column R' to yield a con- 95 stant predetermined vapor temperature as in- dicated by the thermometer 32.

Secondary fractionating column F is con- 100 structed similarly to primary column R' with the exception that a bleeder tray 33 is added at a predetermined intermediate point within the column. The fractionated vapors from line 32 are introduced into the compartment 30 of this column and again ascend through a downflowing stream of colder reflux. From this compartment 30 a portion of the liquid which collects therein is withdrawn for re- fluxing to column R' as just described, while the remainder is withdrawn by a pump and forced through a line 34 via a cooler 35 to storage. This latter material constitutes the heaviest of the desired overhead, or light, cuts.

The bleeder tray 33 is so constructed that a sufficient level of liquid is carried on the tray to permit of drawing off a portion of the same via the line 36, whence it is transferred through line 37 and cooler 38 to storage. This material constitutes the second heaviest of the desired overhead cuts; its quality being maintained by so regulating the rate of bleed- 110 ing as to hold a constant predetermined li- quid temperature on the bled material as de- 115 termined by the thermometer 39.

The vapors leaving the top of the fraction- 120

130

ating column F are carried via the line 40 to the partial condenser 41 wherein the heavier portions are condensed and gravitated via a line 42 to a receiving drum 43, while the lighter remaining oil vapors are led via a line 42' to the condenser 44 where they also are condensed and subsequently gravitated via a line 45 to drum 46. Reflux liquid is pumped via line 47 onto the top tray 48 of fractionating column F to maintain the control on the vapors going to the partial condenser 41, as indicated by the thermometer 49, material from either drum 43 or 46 being used for this reflux, according to the character of the desired finished cuts. The quality of the vapors going to condenser 44 via line 42' is controlled by regulating the quantity of cooling material circulated through the partial condenser 41, this control being maintained by holding a constant predetermined temperature on the vapors in line 42' as indicated by the thermometer 50. Any water which accumulates in drums 43 or 46 is removed by suitable pumps, while the balance of the materials collected at these drums and not required for reflux purposes is removed by other suitable pumps, cooled, and sent to storage via lines 55 and 56 as indicated. These latter materials constitute the two lightest of the desired overhead cuts.

The entire system is carried under a partial vacuum, this being maintained by the steam condenser 51 and the vacuum pump V' which remove the uncondensed steam and fixed gases from the system via line 54.

Any or all of the cuts obtained as described above may be rerun through a similar apparatus for the production of still sharper cut materials and with similar results, the temperatures being varied to suit the desired cuts.

Preparatory to taking up the operation of the process more in detail, it should be noted that the uniqueness of the invention resides at least partially in the following items:

1. Heating the feed above a very definite lower temperature limit to obtain the desired sharp cut between residual and overhead products; the amount of this necessary heating varying, of course, with each feed material and character of desired overhead products, as more fully developed hereinafter.

2. The use of a special type of exhausting heating unit in conjunction with a combination of exhausting and fractionating column sections; this special exhausting heating unit consisting of an apparatus wherein the evolved vapors required for the exhausting operation are separated from the residual liquid in a separating element apart from the heating elements of the exhausting heater—the residual liquid being subsequently removed from the system without its coming again into contact with the aforementioned exhausting heating elements. This facilitates

proper temperature control and efficient use of fuel.

3. The recognition of the fact that cracking must be suppressed at the exhausting heater if the desired sharp cut between residual and overhead products is to be obtained.

4. The elimination of the storage of any appreciable volumes of oil within the system, whereby control adjustments may be quickly obtained.

In the exhausting column phase of the disclosed process, the original feed material must be denuded of a large proportion of its original light material content; the quantity removed being such that the subsequent evolution of vapors at the exhausting vapor separator will eliminate from the residual liquid all of the remaining desired overhead fractions. The removal of this light material content within the exhausting column section occurs in two phases, namely, the initial releasing of the vapors formed by the feed heating operation, and the subsequent evolution and removal of additional vapors through the intimate contact obtained between the liquid feed material and the hotter counter-currently flowing stream of recycling exhausting vapors. The effective operation of the process depends upon the correct balancing of these two vapor releasing phases; if the feed material is heated too much, too heavy vapors will be released at the feed plate, and an excess amount of refluxing will be required at the rectifying columns; if the feed material is heated too little, too great a heating load will be thrown on the exhausting vapor stream, and it will be found impossible to eliminate all of the desired light material fractions from the residual liquid. The error on the side of heating the feed too high wastes heat, but the error on the side of heating the feed too low destroys the distillation efficiency of the system.

If the system is started up with too cold a feed, desired light material fractions will be found in the residual liquid. The first, and natural, move toward correcting this defect in quality would be to fire the exhausting heaters harder. Up to a certain critical point, the raising of the temperature at the exhausting heaters would raise the temperature of the exhausting column bottoms and decrease the light material content of the residual liquid; beyond this point, however, the system would simply overload with recycling exhausting vapors with no apparent improvement in quality of the residual material. When this vapor overloading finally occurs, it is then perfectly obvious that the feed temperature is too low. It is not necessary, however, to fire the exhausting heaters to such an extent in order to test out the correctness of any given feed temperature, since the real test for correctness of feed temperature lies in the character and magnitude of the gap be-

tween the feed temperature and the temperature of the vapors immediately above the feed plate—the system, of course, having first come to an equilibrium with the fractionating columns cutting the desired end point on the overhead products. Under certain conditions, the process will work satisfactorily with a feed temperature somewhat lower than that of the vapors, sometimes as much as 10 75° F., the exact value for this permissible temperature depression varying with each type of feed and character of overhead products. In other cases, a feed temperature depression of as little as 25° F. will make it impossible to clear the residual liquid of all of the desired overhead fractions. Likewise, the feed temperature may under certain conditions be considerably higher than the corresponding vapor temperature, although a temperature which is materially elevated above that of the vapors will always require excessive refluxing. The optimum of correct feed temperature is attained when the feed and corresponding vapor temperatures are exactly the same.

Since a feed temperature depression of only a few degrees may in some cases seriously impair the distillation efficiency of the process, it is deemed good operating practice 30 to carry the feed temperature 2 to 10° F. higher than the corresponding vapor temperature. This elevation of feed temperature is so small that its effect on the thermal efficiency of the process is negligible; at the same time it insures the achievement of a maximum distillation efficiency.

In general, it may be stated that, the larger the percentage of cuts being taken off, the less will be the permissible feed temperature 40 depression below the optimum. For example, a 25% cut of gasoline may be successfully made from a certain California crude oil with a feed temperature depression of 60° F., yet when an additional 15% of kerosene distillate is desired (making a total of 40% overhead) this temperature depression must be reduced to approximately 10° F. On the other hand, the feed may always be heated higher than the optimum at the expense of thermal 50 efficiency only.

Many oil distillation systems make use of a feed material which has been heated in a more or less haphazard degree the primary object of such heating residing in the desire to 55 reclaim waste heat from residual products leaving the system. While this process by no means overlooks the economies resulting from such a heat conservation effect, it goes much farther in recognizing the absolute necessity 60 of controlling the temperature of the feed material within very definite temperature limits (these limits varying, of course, with each particular type of feed material and character of overhead product) for the primary purpose of effecting an economical

clean cut separation between the resultant residual and overhead materials. Furthermore, this feed temperature control is obtained in a very definite manner, namely, by correlating the feed temperature with a corresponding vapor temperature within the wash column or initial fractionating column (the vapor temperature control being preferably, but not necessarily, taken immediately above the exhausting column feed plate). 70

In this process, the vapors generated by the heating of the exhausting column bottoms are released in a vapor separator apart from the heating elements of the exhausting heater. This separation of the exhausting vapors subsequent to their evolution offers the following advantages:

1. The temperature difference between the exhausting column bottoms and the residual liquid in the vapor separator often amounts to 100° – 150° F. By heating the exhausting column bottoms in counter-current contact with the heating medium, this temperature difference may be utilized to produce correspondingly lower exit temperatures of the heating medium (flue gases for example) with a corresponding increase in heating efficiency. 85

2. The heating of the exhausting column bottoms previous to the releasing of the evolved vapors makes it possible to use a tubular construction for the exhausting heater—resulting in high capacity, high fuel efficiency economies common to all tubular heater installations. In addition, the use of such a tubular heater also makes it possible to operate the exhausting unit at high temperatures without encountering local overheating troubles. 95

3. In many distillation operations of the process, the exit temperatures carried on the residual liquid are at or just under the incipient cracking temperature. 105

Under such circumstances, if a portion of the residual material was recycled and held at this temperature, it would gradually break down. With the once-thorough heating, however, the period of time during which the residual material is held at its maximum temperature is so short that no 110 noticeable cracking occurs.

4. Samples for determining the quality of materials being made in the exhausting column or vapor separator are immediately 115 available for control purposes. 120

5. Changes in the exhausting control of the process can be very quickly and easily made due to the small volume of liquid carried in the apparatus.

6. The control on the exhausting heater 125 can be automatically maintained.

The primary duty of the exhausting column, as above mentioned, is to denude the original feed material of such a proportion of its light material content that all of the 130

desired light fractions will be eliminated from the residual material at the exhausting vapor separator. The elimination of these light fractions from the residual material requires the presence of comparatively heavy equilibrium vapors within the vapor separator. If these equilibrium vapors should contain any substantial amount of light fractions, a portion of the same would remain in the liquid, and the desired sharp cut between overhead and bottoms would be lost. Obviously, then, if any substantial amount of cracking occurs at the exhausting heater, light cracked fractions will be present in the exhausting vapor separator, to the detriment of the residual liquid specifications. In addition, it should be noted that this process is specifically and solely a distillation process—developed for the purpose of sharply separating various oil fractions originally held in solution with each other within a single feed material. For these reasons, the process is always operated in such a manner as to eliminate, to the best of the operator's knowledge, all tendencies toward cracking at the exhausting units.

As previously indicated, the effective operation of the process requires the use of the exhausting heating units in conjunction with exhausting and fractionating columns. In operating such a system, just sufficient reflux is used at the fractionating columns to give the desired end point and sharpness of fractionation to the overhead cuts, the temperature of the feed to the exhausting column is held at approximately that of the vapors above the feed plate, and the exhausting heaters are fired at the lowest permissible temperatures yielding the desired residual material cut. Obviously, when starting up a unit, when the character of the feed material changes, or when a change is desired in the character of the distillation products, the control on the system must be adjusted until the above balance is obtained. It is during these periods of adjustment of control that the described elimination of the storage of any appreciable volumes of oil within the system is most keenly appreciated.

After establishing a preliminary temperature adjustment of the system, if large bodies of oil were held at the base of the rectifying columns and exhausting vaporizer, the unit would have to be operated for a considerable period of time to allow these bodies of material to come to equilibrium under the new temperature conditions; then test samples would be taken, the control readjusted, and another period of waiting gone through with while the bodies of oil again came to another equilibrium. With such an operation, many hours would elapse before the system could be brought into correct operating control, with a consequent large production of off specification materials and loss of effective

operating time. Although such a procedure appears absurd, in light of the obvious fact that representative samples of the new temperature control could be taken almost immediately from a system wherein the storage feature is eliminated, it represents the routine necessarily followed when operating the typical "column fed" shell still in conjunction with a simple fractionating column. Even the most casual comparison should readily reveal the superiority of the once through, tubular heated, non-storage features of the disclosed process as contrasted with the long time heating contact, shell fired, large storage features of the typical "column fed" shell unit.

In addition to the time and material savings indicated above, the elimination of the storage of any appreciable bodies of oil within the system materially increases the sensitiveness of the same to slight temperature changes on the part of either vapors or liquid. This sensitiveness to temperature variation makes it possible to automatically control the character of the distillation products within very close specification limits.

As a result of this process, the heavy residual cuts obtained from the vapor separator S show no overlap by the standard Engler distillation test when compared with the overhead cuts obtained from the primary rectifying or fractionating column R; in fact, a gap of 6°-10° F. is not unusual.

As an example of cuts which may be obtained from a given feed, a pre-heated intermediate distillate of 34.8° A. P. I. was introduced on the feed plate 5 in tower E at a temperature of 425° F., this temperature being two degrees higher than the temperature of the vapors immediately above said plate. The vapors withdrawn through the line 22 at the top of said tower E had a temperature of 395° F. while those discharged from the reflux condenser 23 to the condenser C had a temperature of 365° F. The bottoms were withdrawn from the chamber 9 at the bottom of the column E at a temperature of 480° F. and a gravity of 35.6° A. P. I. These bottoms after being heated in a tubular exhausting heater H were introduced at a temperature of 560° F. into the separator S from which vapors at 535° F. were introduced into the chamber 9 of said column E. The residual material withdrawn from the bottom of separator S through the line 19 had a temperature of 547° and a gravity of 33.5° A. P. I. The gasoline recovered from condenser C which had a gravity of 44° A. P. I. and constituted 11.8% out of a possible 12% of the original feed, had an end point by the standard Engler distillation test of 444° F.; while the 88.2% of residual material of the separator S had an initial vaporization temperature of 450° F. Thus, in this case the gap between the two cuts was 6° F. In an-

other instance with another intermediate distillate feed material the end point of the light cut was 428° F., and the initial point of the heavy cut was 438° F., the gap thus being 10°.

In the case of a crude petroleum having a gravity of 23.2° A. P. I., this material was preheated and passed at a temperature of 430° F. onto the plate 5 of the apparatus shown in Fig. 4 wherein the temperature of the vapors above said plate was approximately 430° F. Vapors were withdrawn from the top of column E and introduced into the base of the column R' at 425° F. while the vapors withdrawn through line 32 had a temperature of 360° F. The gasoline from these vapors amounted to 20% of the feed material and had a gravity of 54° A. P. I. The bottoms were withdrawn from the chamber 9 in the base of column E at a temperature of 475° F. and were elevated in the heater H to a temperature of 590° F. at which temperature they were introduced into the vapor separator S. The separated vapors withdrawn from the separator S were introduced into the chamber 9 at a temperature of 585° F. The residual material withdrawn from the base of separator S had a gravity of 17.1° A. P. I. and represented 78% of the feed. The water content of the feed was 1% and the loss resulting in the operation of the process was 1%. The end point of the gasoline recovered as a composite from the lines 36 and 40 was 420° F., and the initial of the residual material from the separator S was 430° F. Thus, in this case, wherein a crude material was treated, the gap between the residual and overhead cuts was 10° F.

From these examples, it may be readily seen that very sharp cuts showing absolutely no overlap by the Engler test may be obtained by the present process.

I claim:

1. A method for the fractional distillation of petroleum oils comprising preheating an oil and introducing the same into an exhausting column in which lighter constituents are liberated, the temperature of the oil approximating that of the vapors in the column at the point of introduction of the oil, passing heated vapors through said column for the purpose of releasing lighter constituents therefrom, withdrawing the bottoms from said column and heating without cracking the same by a once-through passage in a coil to generate a quantity of vapors, separating said vapors and employing the same as said heated vapors for passage through said column to release said light constituents.

2. A method for the fractional distillation of petroleum oils comprising preheating an oil approximately to a definitely predetermined elevated temperature and introducing the same into a rectifying column in which lighter constituents are liberated, pass-

ing hot distilling vapors through said column for the purpose of releasing lighter constituents and all the lightest constituents, withdrawing the bottoms from said column and, by a once-through passage in a coil, heating the same without cracking to generate a quantity of hot distilling vapors, separating said hot vapors and employing the same as those relatively hotter vapors which are used to release lighter constituents.

3. A method for the fractional distillation of petroleum oils comprising preheating an oil and introducing the same into an exhausting column in which light constituents are liberated in the form of vapors, the temperature of the oil approximating that of the vapors in the column at the point of introduction of the oil, withdrawing the bottoms from said column, heating without cracking the same by a once-through passage in a coil to generate a quantity of hot distilling vapors, separating said hot vapors and passing the same through said column countercurrently to the movement of the oil for the purpose of releasing lighter constituents therefrom.

4. A method for the fractional distillation of petroleum oils comprising preheating the oil, introducing the preheated oil into a column in which vapors are liberated, said column having an exhausting section below the point of introduction of the oil and a washing section above the point of introduction of the oil, the temperature of the oil approximating that of the vapors in the column at the point of introduction of the oil, withdrawing the bottoms from the base of said column, heating without cracking the same by a once-through passage in a coil to generate a quantity of hot distilling vapors, separating said hot vapors from the residual material and passing the vapors so separated up through said exhausting section for the purpose of liberating lighter constituents from the introduced oil.

5. A method for the fractional distillation of petroleum oils comprising preheating an oil, introducing the same into an exhausting column in which the lighter constituents are liberated therefrom, the temperature of the oil closely approximating that of vapors in the exhausting column at the point of introduction of the oil whereby the lightest constituents are liberated at said point of introduction, rectifying liberated vapors beyond said column and returning the reflux to the upper portion of the column, withdrawing the bottoms from the base of the column and heating without cracking the same by a once-through passage in a coil to generate a quantity of hot distilling vapors, separating said vapors from the residual material and passing said hot vapors up through said column for the liberation of lighter constituents from the oil flowing down through the column.

6. A method for fractionally distilling petroleum oils for the purpose of obtaining a

sharp cut between a relatively heavy residual product and a relatively light overhead product, comprising preheating an oil, introducing the same into a distilling column above an exhausting section thereof wherein light 5 constituents of the oil are liberated, allowing the oil to descend through said exhausting section while in intimate countercurrent contact with an ascending stream of relatively 10 hotter vapors for the purpose of further removing light constituents, withdrawing the resultant liquid bottoms from the base of the column, heating without cracking the bottoms by a once-through passage in a coil to 15 generate the aforementioned vapors, separating the vapors from the remaining residual liquid at a place apart from the place of heating, returning the separated vapors to the base of the exhausting section of the distilling 20 column to serve as said relatively hotter vapors, removing the residual liquid from the system, said liquid constituting the desired heavy residual product, introducing the vapors arising from the exhausting section 25 above the point of oil introduction into a fractioning section, washing and fractioning these vapors to remove the undesirable heavy fractions entrained and evaporated in the exhausting section by bringing them into intimate 30 countercurrent contact with a relatively colder reflux liquid introduced into the top of the fractionating section, feeding the bottoms from the fractionating section, into the upper portion of the exhausting section, 35 withdrawing the vapors from the top of the fractionating section and condensing them to form the desired light overhead product.

7. A method for the fractional distillation of petroleum oils, comprising preheating an 40 oil approximately to a definitely predetermined elevated temperature and introducing the same into a rectifying column in which lighter constituents are liberated, passing hot distilling vapors through said column for the 45 purpose of releasing lighter constituents and all the lightest constituents, withdrawing the bottoms from said column and, by a once-through passage in a coil, heating said bottoms without cracking to generate a quantity 50 of hot distilling vapors, separating the liquid portions of said bottoms from said hot vapors, removing said liquid portions from the system without recycling the same to the coil, and employing said separated hot vapors as 55 the hot distilling vapors which are used to release said lighter constituents.

Signed at Los Angeles, in the county of Los Angeles and State of California, this 1st day of November, A. D. 1926.
